UNITED STATES PATENT OFFICE.

ELON J. VAN FLEET, OF JOLIET, ILLINOIS, ASSIGNOR TO WILLIAM E. PRATT, OF CHICAGO, ILLINOIS.

LUGGAGE CARRIER FOR AUTOMOBILES.

Application filed April 10, 1922. Serial No. 550,988.

To all whom it may concern:

Be it known that I, ELON J. VAN FLEET, a citizen of the United States, residing at Joliet, in the county of Will and State of Illinois, have invented certain new and useful Improvements in Luggage Carriers for Automobiles, of which the following is a specification.

This invention relates to improvements in luggage carriers for automobiles and its purpose is to provide an improved device adapted to be attached to the running board to form an enclosure in which suit cases and other articles may be placed. An important object of the invention is to provide a luggage carrier embodying improved means for attaching it to the running board. A further object is to provide a device embodying gripping jaws which may be caused to engage the running board by operating mechanism located above the running board. Still another object is to provide an improved construction which may be easily and conveniently folded into compact form when not in use. Other objects relate to various features of construction and arrangement which will appear more fully hereinafter.

The nature of the invention will be understood from the following specification taken with the accompanying drawings in which one embodiment is illustrated. In the drawings:

Fig. 1 is a perspective view of the invention applied to the running board of an automobile;

Fig. 2 shows a transverse vertical section through the running board and the gripping jaws at one end of the carrier, illustrating the end wall of the device in elevation;

Fig. 3 is a transverse vertical section through the gripping jaws which are attached to an intermediate part of the side wall of the carrier;

Fig. 4 is a detail sectional view on the line 4—4 of Fig. 1.

Fig. 5 shows a top plan view of one of the lower jaw members;

Fig. 6 shows a longitudinal section on the line 6—6 of Fig. 5;

Fig. 7 shows a top plan view of one of the upper jaw members; and Fig. 8 shows a sectional view on the line 8—8 of Fig. 7.

As illustrated, the invention is shown ap-

plied to an automobile comprising a body 10, side doors 11, a running board 12, and a rear wheel fender 13. The luggage carrier comprises a side wall 14 in the form of a lazy tongs made up of a plurality of bars 15 which are pivotally connected at intermediate points by rivets 16 and at their ends by rivets 17, the bars being spaced apart at the intermediate pivotal points by washers 16^a, to reduce the friction. The extremities of the bars 15 at the ends of the side walls 14 are pivoted at points 18 to the projecting ears 19 carried by sleeves 20 which are mounted on and rotatably engaged by vertical rods or posts 21.

The lower end of each rod 21 rotatably engages the hub 22^a of an upper jaw member 22 which is adapted to overlie the upper surface of the running board 12, being provided with a shoulder 22^b adjacent the hub 22^a to abut against the side of the running board. The lower extremity of each rod 21 threadedly engages a lower jaw member 23 which projects inwardly and is provided with an upturned extremity 23^a adapted to engage the under side of the running board, the contacting surface of this extremity preferably being serrated. The outer end of each lower jaw 23 is provided with an upwardly projecting tongue 23^b which is adapted to engage the slot or recess 22^c formed between the lugs 22^d which are carried by the hub of the adjacent upper jaw member 22. Each rod 21 is provided above the jaw members with an enlarged part 24 which has a square or other non-circular contour, adapted to be engaged by a wrench so that the rods 21 may be conveniently rotated to adjust the relative positions of the upper and lower jaw members 22 and 23 respectively. It will be apparent that upon rotating the rods 21 in the proper direction, the upper and lower jaw members will be caused to grip the running board and thereby secure the device firmly in position.

The tongues 23^b which interlock with the lugs 22^d on the upper jaw members prevent relative rotation of the jaws of each pair when the rods 21 are rotated; and the use of an upturned serrated extremity 23^a on each lower jaw, located some distance inwardly from the edge of the running board, operates to bring about an effective grip in a vertical direction.

In addition to the gripping jaws which

are operated by the vertical rods 21, it may be desirable in some instances to use an intermediate set of jaws 25 which are similar in construction to those located at the 5 ends of the device except that they are operated by a short threaded rod 26 having a squared upper extremity 26^a adapted to be engaged by a wrench. This rod is provided with a collar 26^b beneath the part 26^a, and 10 a clip 27 is adapted to be engaged by the rod between this collar and the upper jaw member. This clip has an upturned flange which is connected to one of the pivots 17 of the lazy tongs which form the side wall. 15 In this way an intermediate support is provided for a luggage carrier of considerable length.

In the embodiment shown the device is provided with one end wall 28 comprising 20 two transverse frame members 29 connected to two vertical frame members 30 and 31. The transverse members 29 are connected to or formed integrally with sleeves 32 which are rotatably engaged by one of the rods 21. 25 The sleeve 32 carried by the lower member 29 may preferably lie immediately above the part 24 of the rod which is adapted to be engaged by a wrench. To maintain the end wall 28 in a position at right angles to 30 the side wall 14, the vertical frame member 31 is extended downwardly and connected at the point 33 to the inner extremity of the upper jaw member 22. If desired, an end wall 28 may be employed at each end of the 35 luggage carrier, but where the device is assembled in proximity to one of the fenders 13, as shown in Fig. 1, only one end wall is necessary to form a complete enclosure.

The invention has the advantage that 40 there are no projecting lugs or screws beneath the running board to be bent or put out of operation by objects encountered during the travel of the automobile. The jaws by which the device is secured to the running 45 board are operated from a position above the running board and the rods 21 which operate these jaws may be conveniently rotated by a wrench or the like. The well-known lazy tongs construction permits the extension 50 of the side wall to any desired length and also permits the folding of the device into a compact arrangement when it is not in use. When thus folded, the jaws 22 and 23 may be rotated about 55 their operating rods until they lie in the plane of the folded side wall 14, and the end wall 28 may be brought into a position parallel with this side wall. A further 60 feature of the device is that there are no projecting screws or pins to engage and injure the articles which are placed within the enclosure on the running board.

Although one embodiment of the invention has been shown and described for purposes of illustration, it will be understood 65 that it may be constructed in various other forms without departing from the scope of the appended claims.

I claim:

1. A luggage carrier comprising a side 70 wall, a rod engaging said side wall, and a pair of jaws operated by said rod.

2. A luggage carrier comprising a side wall, a rod connected to said side wall, a jaw rotatably engaged by said rod, and 75 a second jaw threadedly engaged by said rod.

3. A luggage carrier comprising a side wall, a rod connected to said side wall, a jaw 80 rotatably engaged by said rod, a second jaw threadedly engaged by said rod, and means for preventing relative rotation of said jaws.

4. A luggage carrier comprising a side wall, a rod connected to said side wall, a pair 85 of jaws connected for operation by said rod, and an end wall connected to said rod.

5. A luggage carrier comprising a side wall, a rod connected to said side wall, a pair 90 of jaws connected for operation by said rod, and an end wall carried by said rod and one of said jaws.

6. A luggage carrier comprising an extensible side wall, rods rotatably engaging the ends of said wall, upper jaw members 95 rotatably engaged by said rods, lower jaw members threadedly engaged by said rods, and means for operating said rods at points above said jaw members.

7. A luggage carrier comprising a side 100 wall, a vertical rod, sleeves mounted on said rod and connected to said side wall, an upper jaw member rotatably engaged by said rod and adapted to coact with the upper surface and lateral edge of a running board, a lower jaw member threadedly engaged by 105 the lower extremity of said rod and adapted to grip the under side of said running board, and means for preventing relative rotation of said upper and lower jaw members.

8. A luggage carrier comprising a side 110 wall, a vertical rod, sleeves mounted on said rod and connected to said side wall, an upper jaw member rotatably engaged by said rod and adapted to coact with the upper surface and lateral edge of a running board, a lower jaw member threadedly engaged by 115 the lower extremity of said rod and adapted to grip the under side of said running board, one of said jaw members having a pair of lugs projecting therefrom, the other jaw member having a tongue adapted to extend between said lugs to prevent relative rotation of said jaw members.

ELON J. VAN FLEET.
